UNITED STATES PATENT OFFICE.

GEORGE P. HEMSTREET, OF HASTINGS-UPON-HUDSON, NEW YORK, ASSIGNOR TO
INTERNATIONAL PAVEMENT CO., OF HARTFORD, CONNECTICUT, A CORPORA-
TION OF CONNECTICUT.

GRAPPLE.

1,413,225.

Specification of Letters Patent. Patented Apr. 18, 1922.

Application filed June 20, 1919. Serial No. 305,656.

To all whom it may concern:

Be it known that I, GEORGE P. HEMSTREET, a citizen of the United States, and a resident of Hastings-upon-Hudson, in the county of Westchester and State of New York, have invented an Improvement in Grapples, of which the following description, in connection with the accompanying drawings, is a specification, like characters on the drawings representing like parts.

This invention relates to grapples or tongs for hoisting purposes. While the principles of the invention are adaptable to tongs designed for various purposes, I have here chosen for purposes of illustration a design more particularly intended for lifting piles of brick, each pile as a unit.

My invention will best be understood by reference to the following description taken in connection with the accompanying drawings wherein:

Figure 1 is a side elevation of a grapple illustrating my invention, with a part broken away;

Fig. 2 is an end view thereof as seen from the right in Fig. 1;

Fig. 3 is a section on the line 3-3 of Fig. 1;

Fig. 4 is a section on an enlarged scale on line 4-4 of Fig. 1; and

Fig. 5 is a section on an enlarged scale on line 5-5 of Fig. 2.

Referring to the drawings, I have there shown a grapple adapted to lift a pile of brick by the engagement of opposed clamping members with the bricks in the bottom layer of the pile in well known manner; and for purposes of illustration I have shown a grapple in which both clamping members are movable, moving toward or from each other when the grapple is operated.

As herein shown, the clamping elements of the grapple comprise two swinging arms 7 and 9 conveniently formed as best shown in Fig. 3 of a pair of channels placed back to back but held in spaced relation by straps 11. To engage the load, the arms may be provided with gripping faces and herein the arm 7 is provided with a fixed transversely extending gripper bar 13, while the opposite arm 9 is provided with gripping means having provision for equalizing the pressure between it and the bar 13 to compensate for any irregularities of the load.

Herein (see Fig. 5) there is provided a transverse bar 15 at the lower end of arm 9 pivoted centrally on a vertical pivot 17 and normally positioned parallel to the opposed bar 13 by means of springs 19 interposed between the bar 15 and the abutment 21 also carried by the lower end of the arm 9. In the embodiment of the invention shown the bar 15 does not directly engage the load but is provided at either end with a shoe 23 having a suitable gripping face 25, as best shown in Fig. 1, and pivoted to the bar 15 on a vertical pivot 27. The shoes 25 are also normally positioned parallel with the opposed gripping face of the bar 13 by means of suitable springs 29 interposed between the ends of the shoes on either side of their pivots and the front of the bar 15.

To provide additional support for the shoes 23, they may be provided with suitable ears 31 between which are pivoted rods 33 supported at their upper ends in brackets 35 on the arm 9.

The swinging arms 7 and 9 swing about suitable bearings which I have herein shown as consisting of blocks 37 adapted to be received between the channels of which the arms are composed and having trunnions receiving and supporting the channels. Means are provided for relatively positioning the blocks 37, which means desirably provide for adjustment of the same toward and from one another; and herein I have shown the two blocks as constituting nuts receiving, respectively, the right and left threaded portions of a rod 39 directly connecting the blocks 37 and relatively positioning the same. The rod 39 may be provided with a hand wheel 40 permitting the adjustment of the blocks toward and from one another in the manner of a turnbuckle.

The arms 7 and 9 are operated to clamp the load by a suitable lever system actuated by the strain developed through the hoisting mechanism with which the grapple is used. Herein this system takes the form of two bell cranks 41 and 43 pivoted at 45 and 47 adjacent the upper ends of the arms 7 and 9 and between the channels from which these arms are formed. The shorter arms of the bell cranks are pivoted to and find a bearing in a transversely extending frame member 49 which may consist, as best shown in Fig. 4, of two plates separated by

suitable spacing sleeves 51, the plates receiving between them, as shown in Fig. 2, the shorter arms of the bell cranks 41 and 43. The longer arms of the bell cranks extend 5 inwardly and may conveniently extend past each other at the center of the frame to provide a powerful mechanical advantage; and for this purpose one of the levers, as 41, may be bifurcated at its outer end, herein 10 as shown in Fig. 3 by being provided with the separate and attached tine portions 53 receiving between them the opposite end of lever 43.

The bell cranks 41 and 43 may be connected by suitable links 55 with a shackle 57 adapted to receive the hook of a hoist in such manner that the weight of the load when the hoist is operated will, through the links 55, draw upwardly on the long 20 arms of the bell cranks, rocking the same about their fixed pivots on the frame member 49 and thus thrusting outwardly the upper ends of arms 7 and 9 and causing the inner ends to approach each other and 25 clamp the load as will be well understood by inspection of Fig. 1.

The construction described permits a ready adjustment of the grapple arms to the size of the load to be lifted by means of the rod 39, the trunnion blocks 37 being moved directly toward each other in a right line. The adjusting means is very simple and leaves the space between the arms which is to receive the load entirely unobstructed. This 35 initial adjustment permits the use of a great mechanical advantage through the levers 41 and 43, since only a very short travel of the gripping faces of the grapple arms is necessary. Consequently, an enormous 40 gripping power may be applied to the lower ends of the gripper arms through the bell cranks.

To permit the grapple to be moved by the hoisting apparatus without clamping action, 45 a suitable latching means may be provided, herein exemplified by the bar 59 carried by the pivot of shackle 57 and having a hook 61 adapted to engage a pin 63 on the frame member 49, thereby to prevent the levers 50 41 and 43 from being drawn upwardly. The pin 63 may conveniently be directly beneath the pivot of shackle 57 and the bar 59 may be provided with a hanging, cam-like nose portion 65 adapted to ride over 55 the pin 63 to permit the same to enter the throat of the hook. To prevent engagement of the latch when such action is not desired, the slideable keeper 67 may be provided, attached to the bar 59 by a pin and 60 slot connection and adapted to close the throat of the hook. If the keeper 67 is withdrawn, the pin 63 when the grapple is lowered will ride along the oblique nose portion 65 of the bar until it comes opposite 65 the throat of the hook, when the bar will

be permitted to swing under gravity to a vertical position so that the hook engages about the pin.

Herein I have shown (see Fig. 1) abutment plates 69 supported by brackets 71 projecting inwardly from the inner faces of the swinging arms 7 and 9 and adapted to engage the upper surface of the load when the grapple is lowered over it. There are thus provided gages for positioning the lower ends of the arms which carry the load-clamping surfaces. Thus, in the illustrative example wherein the grapple is designed for lifting piles of brick, the clamping face of the bar 13 and the clamping faces 25 of the shoes 23 would be so positioned as accurately to engage the lowermost row of the pile of brick. In the example shown, furthermore, wherein these abutment elements are located below the pivots of the swinging arms 7 and 9, the engagement thereof with the top of the load will tend to swing these arms in such a manner as to clamp the load between them, thus providing for an initial engagement of the grapple with the load. When the hoisting pressure is applied, therefore, this initial engagement will prevent the arms from sliding upwardly along the sides of the load before the lever system can act to apply an adequate clamping pressure thereto.

To permit the deposit of articles handled by the grapple in regular order with suitable spaces between, suitable gage means may be utilized projecting from the side 100 of the grapple; and I have herein (see Fig. 1) shown a sector 73 pivoted between the channels which make up the arms 7 and 9 and provided with an exterior operating handle 75. The sector may, if desired, be 105 swung out of the way between the channels or moved to the projecting position shown, a set screw 77 or other suitable clamping means being provided for securing it in adjusted position.

It will be noted that in the design of 110 grapple shown the operating mechanisms including the various swinging levers of the system are disposed inwardly between the arms 7 and 9, thus making possible the 115 utilization of the gage element 73, as shown.

Having thus described in detail an illustrative embodiment of my invention, the principles exemplified thereby which I claim as new and desire to secure by Letters 120 Patent I shall express in the following claims:

1. A grapple comprising a frame, bell cranks each having an arm pivoted on said frame and having other arms extending inwardly, depending grapple arms mounted on the axes of said bell cranks, lower pivot bearings for said arms and a spacing connection between said bearings.

2. A grapple comprising a frame, bell 130

- cranks each having an arm pivoted on said frame and having other arms extending inwardly, depending grapple arms mounted on the axes of said bell cranks, lower pivot 5 bearings for said arms and an adjustable spacing connection between said bearings.
3. A grapple comprising a frame comprising a pair of spaced plates, levers pivoted between the plates, depending grapple arms 10 also comprising spaced plates and receiving between them portions of said levers to which the said arms are pivotally connected, said plates also receiving between them trunnioned bearing elements on which the 15 grapple arms may swing and a spacing connection between said elements.
4. A grapple comprising a frame comprising a pair of spaced plates, levers pivoted between the plates, depending grapple arms 20 also comprising spaced plates and receiving between them portions of said levers to which the said arms are pivotally connected, said plates also receiving between them trunnioned bearing elements on which the 25 grapple arms may swing and a right and left threaded adjusting rod between said elements.
5. A grapple comprising a pair of grapple arms pivoted between their ends, said arms 30 comprising spaced plates, an operating lever system therefor comprising a frame received between the plates of the arms and itself comprising spaced plates, levers received between and pivoted to the plates of the frame 35 and also having portions received between and connected to the plates of the arms, said levers having free end portions for the connection of suspending means.
6. A grapple comprising a pair of pivoted 40 grapple arms and a lever system for moving the same comprising a frame of spaced plates, levers received between and pivoted to said plates and connected to said arms, said levers having arms extending inwardly 45 and one having a bifurcating portion receiving the extremity of the other.
7. A grapple comprising a movable clamp jaw having gripping shoes pivoted thereon to swing transversely thereof, springs supporting the shoes and normally restraining their pivoting movement whereby the grapple 50 may grip a surface disaligned with the jaw.
8. A grapple comprising a clamp element, 55 an opposed swingable arm and a transversely extending clamp element pivoted on a vertical pivot to said arm.
9. A grapple comprising a clamp element, an opposed swingable arm provided with a transverse, spring-positioned clamp element 60 provided to swing transversely.
10. A grapple comprising a clamp element, an opposed swingable arm provided with a transverse, spring-positioned clamp element 65 provided to swing transversely having pivoted, spring-supported, gripping shoes on either side thereof.
11. A grapple comprising a clamp element, an opposed swingable arm provided with a transverse bar supporting at either side 70 thereof, spring-positioned, gripping shoes pivoted for transverse swinging movement.
12. A grapple for lifting and transporting commodities having devices for clasping the load which are releasable to deposit the 75 load and an adjustable gaging element projecting outwardly from the side of the grapple for positioning it relatively to an exterior object such, for example, as a previous load whereby the commodities transported 80 can be regularly arranged.
13. A grapple for lifting and transporting commodities comprising depending arms pivoted between their ends, a tension operated lever system disposed between the upper ends of the arms and a gaging element 85 projecting outwardly from one of said arms to position the grapple relatively to an exterior object prior to the release of the load.
14. A grapple having an adjustable 90 gaging element projecting from a side thereof comprising a pivoted sector having means for clamping it against rotation.
15. A grapple comprising a clamp element and an opposed movable clamp element comprising a pivoted arm, tension-operated 95 means for swinging said arm and an inwardly projecting abutment on said arm adapted to engage a load, said abutment being located below the pivot of the arm 100 whereby its engagement with the load will apply a preliminary clamping pressure thereto.
16. A grapple comprising a clamp element and an opposed movable clamp element 105 comprising a pivoted arm, tension-operated means for swinging said arm and an inwardly projecting abutment on said arm adapted to engage a load and providing a gage for positioning the lower end of the 110 arm.

In testimony whereof, I have signed my name to this specification.

GEORGE P. HEMSTREET.

Certificate of Correction.

It is hereby certified that in Letters Patent No. 1,413,225, granted April 18, 1922, upon the application of George P. Hemstreet, of Hastings-upon-Hudson, New York, for an improvement in "Grapples," errors appear in the printed specification requiring correction as follows: Page 3, line 61, claim 9, for the word "provided" read *pivoted*; same page, line 65, claim 10, for the word "provided" read *pivoted*; and that the said Letters Patent should be read with these corrections therein that the same may conform to the record of the case in the Patent Office.

Signed and sealed this 16th day of May, A. D., 1922.

[SEAL.]

KARL FENNING,

Acting Commissioner of Patents.
